PAPER ROLL HOLDER

Filed June 13, 1927

UNITED STATES PATENT OFFICE.

JOHN RUZE, OF NEW YORK, N. Y.

PAPER-ROLL HOLDER.

Application filed June 13, 1927. Serial No. 198,633.

This invention relates to paper roll holding receptacles and in particular to one adapted for use in stores or other places where the paper is to be dispensed and torn off to the required size for use.

A particular object of the invention is to provide a paper roll holding receptacle which will keep the rolls of paper clean and which will allow the same to be drawn off and torn cleanly at the length desired by the user.

A still further object of the invention is to provide a receptacle having a hinged door which will act as a weight or drag so that the same, when used in connection with the paper to be drawn off will retard its too free movement and will allow it to be drawn off the roll evenly and cut cleanly at its point of severance.

A still further object of the invention is to provide a receptacle having a yieldable closure which allows the paper to be drawn out but which normally conceals the paper at the point where it is to be gripped, the cover of the receptacle also acting to entirely conceal the paper edge so that it is not evident that the receptacle is used for paper roll holding purposes.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in perspective of my improved paper roll holding receptacle, a piece of paper being shown in its drawn out position in outline.

Figure 2 is a section taken on the line 2—2 of Figure 1, the view being enlarged to show in detail the position of the roll held in the receptacle.

Figure 3 is a section taken on the line 3—3 of Figure 1 and shows in elevation the roll holding arrangement within the receptacle, the illustration being reduced in length for purposes of convenience in illustration.

Figure 4 is an enlarged fragmentary detail view of the rear side of the cover showing the spring pressed closure member and the method of operating the same.

Figure 5 is a sectional edge view of the

mechanism shown in Figure 4 and shows how the spring and resilient closure member are associated with the cover of the receptacle.

Figure 6 is a section taken on the line 6—6 of Figure 1 showing the construction of the lower end of the door and the paper holding shelf of the receptacle itself.

Figure 7 is a fragmentary view in section of a corner of the cabinet showing the method of hinging the door to the cabinet wall.

Referring to the drawings in detail, 5 indicates the paper holding receptacle which is of the usual box construction, the top thereof being provided with openings 6 having extended portions 7, so that the receptacle 70 can be positioned beneath a counter and through the medium of screws may be detachably secured to the counter. The front of the receptacle 5 is provided with an opening, bounded on the upper edge by a bead 8 and 75 on the lower edge by an upstanding flange or lower portion 9, the opening being arranged to receive a door 10, the lower half of which is bent to extend inwardly at an angle from the vertical, the door or closure at the bottom thereof being bent upon itself as at 11 to form an inwardly extending flange, the outer extension thereof providing an extended flange 12 which acts as a paper tearing edge, the flanges 11 and 12 forming a single 85 paper holding flange or foot which extends entirely across the door 10 and is adapted to rest upon a flange 13 formed on the upper end of the lower portion of the front wall 9 of the receptacle. This flange 13 is formed 90 similar to the paper holding flange and is arranged to provide what might be called a paper holding shelf over which the paper slides when the same is drawn from the roll.

It will be noted that the cover 10 is provided with a rolled upper edge which is adapted to receive at its ends the headed pins 14 which pass through suitable elongated openings 14-A in the side walls of the cabinet to thereby allow play of the door 10 100 vertically and this play is sufficient to allow the door to rest upon the paper holding shelf 13 so that a friction drag is created when the paper is drawn from the roll, due to the weight of the door, the paper holding flange 105 12 is cut out as at 15 at its center to provide a space where the edge of the paper may be gripped by the fingers preparatory to drawing the same from the roll and in order that a single cutting edge may be presented when 110

the paper is to be severed, I have provided a yieldable filter piece 16 which is slidably mounted on the flange 12 and is guided at its side edges by the guide pieces 17 which are suitably secured to the flange 12 or may be formed by bending the material up out of the flange 12. These guides overlie the edge of the cutter piece 16 and allow its free sliding movement forwardly and rearwardly to uncover that portion of the paper lying in the opening 15 of the flanges 12 and 13 as it is of course understood that the lower flange 13 will also be cut out to coincide with the cut out portion of the flange 12 so that the paper disposed therein may be gripped preparatory to drawing the same from the roll.

In order to normally maintain the cutter piece 16 in its extended position, I have provided a piece of spring steel 17 which is secured to the rear face of the cover 10 through the medium of tongues 18-A punched there out of, the lower end of the spring 17 engaging the upturned flange 18 at the rear of the cutter piece, a similar flange 19 being formed at the front thereof so that the cutter piece can be manipulated with the thumb when it is desired to push the same rearwardly against the action of the spring 17 to grip the paper positioned in the opening 15. In order to normally retain the cover 10 closed, I provide at each end thereof, a notch 20 and on the end corners of the lower flange 13, I provide an upturned catch 21 which has been punched out of the material of the flange and bent up to provide a catch over which the flange 12 will ride until the notch 20 therein rides over the edge of the catch 21 and allows the flange 12 to rest on flange 13 at which time the flange 12 will underlie the catch 21 due to the normal tendency of the door 10 to hang in vertical position and it will be evident that any drawing on the paper will not cause the door 10 to open and the door 10 will function as a drag on the paper to allow the same to be drawn off evenly from the roll and to also hold it when it is to be torn, as it is understood that when the cutter piece 16 is in its extended position as shown in Figures 1, 2 and 5, a continuous cutting edge will be presented when the paper is to be torn and the paper can be torn cleanly along its width. If desired, the bottom of the receptacle may be used to house a drawer 28 which slides on the ridges 29 formed in the receptacle sides and bottom, the drawer being provided with the usual handle 30 whereby it can be readily opened and closed, the ridges 29 reducing the frictional resistance to a minimum.

In order to properly support the roll within the receptacle, I have provided flange-like brackets 22 formed to provide depressions 23 for the reception of the flattened ends 24 of a tube 25, the latter of which is arranged

to support at its ends, the roll holding spools 26 upon which the roll of paper or other material 27 is suspended. In order to facilitate the drawing off of the paper from the roll, it is essential that the wooden spools 70 revolve on the metallic tube 25 and in flattening the ends thereof and positioning them in the depression 23 of the brackets 22, rotation of the tube is prevented and the free drawing off of the paper can be accomplished. 75 The outer ends of the brackets 22 act as a stop to limit the inward swinging movement of the door 10 when the same is closed.

It is quite evident, therefore, that I have provided a paper roll holding receptacle 80 which presents many advantages over the old form of roll holder, and it will be especially evident that I have provided a paper holding device, the cover of which acts as a drag and holds the paper securely while the 85 same is being torn.

It is also evident that I have provided a construction which may be made of sheet metal, which has few parts, which will not get out of order readily, and which may be 90 replenished with a roll of paper without inconvenience or disarrangement of the parts.

Of course, it is quite evident that two or more rolls of paper of different width can be supported in the receptacle on the same 95 bar which would necessitate the placing at the proper position of two or more cutter pieces or gripper pieces, as they might be termed, and it is quite evident that paper might be drawn off from either one of a 100 variety of rolls used in a receptacle.

It is also evident that I have provided a container for wrapping paper or other paper which is sanitary, presents a better appearance and which will allow gripping of the 105 paper quicker and easier and where various colored paper rolls of different widths are used, will allow the same to be drawn individually, and the receptacle also, by reason of the door construction will accommodate 110 rolls of paper of maximum diameter.

While I have illustrated and described my invention with some degree of particularity, I realize that in practice various alterations 115 therein may be made. I therefore reserve the right and privilege of changing the form of the details of construction or otherwise altering the arrangement of the correlated parts without departing from the spirit of the invention or the scope of the appended claims. 120

Having thus described my invention what I claim as new and desire to secure by United States Letters Patent is:—

1. A paper roll holder comprising a receptacle having a ledge portion and having an opening therein through which the paper is adapted to be drawn, a door hinged for vertical movement in said receptacle and the lower edge of the door providing a cutting edge whereby paper drawn out of the recep- 125 130

tacle can be readily torn, the door being supported on said ledge and acting as a drag on paper drawn over the ledge.

2. A paper roll holder comprising a receptacle, means for supporting a roll of paper therein, a closure for said receptacle having a flange thereon arranged to provide a cutting edge whereby paper drawn thereunder can be severed, a yieldable slide positioned on the flange to complete the cutting edge thereof and said slide being movable to disclose a portion of the paper whereby the same can be gripped for withdrawal and severance.

3. A paper roll holder comprising a receptacle having an opening therein through which paper is adapted to be withdrawn, a door for said receptacle, a projection on the receptacle for supporting the door, the door being supported to act as a drag on the paper drawn over said projection, the lower edge of the door providing a cutting edge whereby paper drawn thereunder can be readily severed, a yieldable slide positioned in the lower edge of the door to complete the cutting edge thereof and said slide being movable to disclose a portion of the paper whereby the same can be gripped for withdrawal and severance.

4. A paper holder comprising a receptacle, brackets in the receptacle, a rod having a flattened end for supporting a roll of paper revolvably thereon, the rod being positioned in said bracket, a closure for said receptacle having an outwardly extending flange thereon, the flange having an opening therein and being arranged to provide a cutting edge whereby paper drawn thereunder can be severed, a yieldable slide positioned at the opening in the flange to complete the cutting edge thereof and said slide being movable to disclose a portion of the paper whereby the same can be gripped for withdrawal and severance.

ing in the flange to complete the cutting edge thereof and said slide being movable to disclose a portion of the paper whereby the same can be gripped for withdrawal and means for latching the door when the same is closed.

5. A paper roll holder comprising a receptacle, a door for said receptacle having an outwardly extending flange thereon, a projection on the receptacle for supporting the door, the door flange having an opening therein and being arranged to provide a cutting edge whereby paper drawn thereunder can be severed and a yieldable slide positioned at the opening in the flange to complete the cutting edge thereof.

6. A paper roll holder comprising a receptacle, a door for said receptacle, said door being flanged at its lower edge to provide a cutting edge, the flange having an opening therein and a yieldable slide positioned in the opening in the flange to complete the cutting edge.

7. A paper holder comprising a receptacle, a closure for said receptacle having an outwardly extending flange thereon, the flange having an opening therein and being arranged to provide the cutting edge whereby the paper drawn thereunder can be severed, a yieldable slide positioned at the opening in the flange to complete the cutting edge thereof and said slide being movable to disclose a portion of the paper whereby the same can be gripped for withdrawal and severance.

In testimony whereof I affix my signature.
JOHN RUZE. [L. S.]
